UNITED STATES PATENT OFFICE

THOMAS O. SCHRADER, OF ALLENTOWN, PENNSYLVANIA, ASSIGNOR TO THE DENT HARDWARE COMPANY, OF FULLERTON, PENNSYLVANIA, A CORPORATION OF PENNSYLVANIA

DESIGN FOR A CLOSURE FASTENER

Application filed September 28, 1931. Serial No. 41,245. Term of patent 14 years.

To all whom it may concern:

Be it known that I, THOMAS O. SCHRADER, a citizen of the United States, residing at Allentown, in the county of Lehigh and State of Pennsylvania, have invented a new, original, and ornamental Design for Closure Fastener, of which the following is a specification, reference being had to the accompanying drawings, forming a part thereof.

Figure 1 is a plan view of a closure fastener showing my new design; Figure 2 is a side elevational view, and Figures 3 and 4 are front and rear elevational views of the same.

I claim:

The ornamental design for a closure fastener substantially as shown.

THOMAS O. SCHRADER.
